FUEL-OIL BURNER

Original application filed July 18, 1924, Serial No. 726,657. Divided and this application filed February 25, 1927. Serial No. 170,835.

This application is a division of our former application Serial No. 726,657, filed July 18, 1924, that matured into Patent No. 1,688,448 on October 23, 1928, and, like the 5 earlier case, has general reference to fuel oil burning apparatus of the class involving an injector burner that is suitably supplied with fuel oil, and a steam generator subjected to a source of heat—as to the burner 10 flame, and wherein the flame of the burner is governed by controlling the amount of heat delivered to the generator.

According to the invention that constitutes the subject of the present application, the 15 amount of heat delivered to the generator is controlled by moving the generator bodily toward and from the source of heat, as toward and from the burner flame; and the general objects are to provide a highly efficient and thoroughly reliable apparatus of 20 the aforesaid class that is compact, and is suitable for use with hot air furnaces, steam boilers, forges, japanning and enameling ovens and the like; to provide fuel oil burning 25 apparatus of the class referred to that is comparatively simple of construction, is economical of manufacture and which may be readily installed in furnaces, boilers, ovens and the like, of prevailing types; and 30 to provide a fuel oil burning apparatus of the principle above mentioned that is automatic in maintaining a substantially constant flame—or one of a given range of variation—and which involves an adjustment 35 whereby the flame—or its range of variation—may be changed.

More specific objects are to provide a support for the generator that is of such nature 40 as will insure freedom of movement so that the generator is sensitive to the moving influence of the actuating medium; and to provide simple mechanism that is convenient of manipulation for changing the mean or average relation of the generator to the 45 source of heat.

The objects above set forth, with others 50 hereinafter appearing, are attained in the construction illustrated in the accompanying drawings wherein Fig. 1 is a sectional

side elevation, and Fig. 2 a front elevation of an embodiment of the invention.

As previously mentioned, the invention is applicable to various types of furnaces or like structures, and, in Fig. 1, the front wall 55 of such a structure is represented by a plate that is designated A. It will be understood from this that the space inside or to the rear of this wall or plate, and in which space the fuel oil burning apparatus is located, 60 constitutes the combustion chamber or firebox of the furnace or the like.

The fuel oil burning apparatus incorporates a hollow casing 1 that is flanged at its forward end and connected to the front plate 65 A, the forward end of said casing being open and registering with an opening a in the front plate that is covered by a suitable closure 2. The casing involves a partition 3 which divides its interior into compartments 70 4 and 5. A combustion chamber 6, preferably constructed of suitable refractory material, is set downwardly in an opening in the top of the casing 1. The front wall of the combustion chamber has an opening 7 75 opposite a burner 8 which is carried by and extends through an aperture in the forward end of the partition 3. This burner is of the well known injector type and includes a steam nozzle 10 and an oil jet 11, the latter 80 receiving fuel oil from a suitable source (not shown) through a pipe 12.

Supported upon brackets 15 that extend rearwardly from the front plate A is a water receptacle 16 which receives its supply of 85 water through a pipe 17 (Fig. 2). The entrance of water to the receptacle 16 is controlled by a valve 18 that is adapted to be closed by mechanism involving a float 19 when the water within the receptacle has 90 attained a given level. A steam generator 20 is supported by arms 21 above the combustion chamber 6, the top wall of the combustion chamber having an opening 22 directly above which the generator is normally positioned. 95 The arms 21 extend downwardly along the opposite sides of the casing 1 and have knife edge bearings 23 that rest in V-notches formed in brackets 24 that extend downwardly and outwardly from the casing 1. At their lower 100

ends, the arms 21 have extensions 25 which carry a cross beam 26. Threaded vertically through the middle of the cross beam is a screw 27 to the upper end of which is applied 5 a cup 28 that receives a stud 29 depending from a bellows 30. This bellows is housed within a cylindrical cavity 31 formed in the bottom wall of the casing 1 and the bellows communicates through a pipe 32 with the 10 receptacle 16. The lower portions of the receptacle 16 and the generator 20 are connected through a flexible conduit 34, while the tops of the vessels are connected through a similar conduit 35. A pipe 36 leads from 15 a part of the latter conduit adjacent the receptacle 16 to the steam nozzle 10 of the burner 8.

To the lower end of the previously mentioned screw 27 is secured a bevel pinion 38 20 which meshes with a similar pinion 39 on a shaft 40, said shaft being journaled in opposed branches of a U-shaped bracket 41 that is carried by the screw 27. The shaft 40 extends through a slot a' in the front plate A 25 and to its forward end is secured a hand wheel 42.

To start the apparatus in operation it is necessary to heat the generator 20 by suitable means, as by a torch, a pilot light or 30 starting burner, or oil pan. These being common expedients, illustration is deemed unnecessary. When steam pressure is created within the generator 20 it is communicated through the pipes 35 and 36 to the nozzle 10 35 of the burner. The steam issuing from this nozzle sucks oil from the jet 11 and atomizes it and the resultant mixture of steam and oil burns within the combustion chamber 6, the products passing through the opening 22 about the generator 20 thus increasing the steam pressure within the generator. The increased pressure now prevailing in the generator is communicated through the pipe 35 to the upper portion of the receptacle 16, and 40 the pressure in the receptacle is transmitted, through the water therein and that within the pipe 32, to the bellows 30, expanding or elongating the bellows and depressing the beam 26. As the beam is depressed, the arms 45 21 will be rocked in a direction to swing the generator 20 out of the direct path of the flame and away from the zone of intense heat. As a consequence the steam pressure will 50 fall within the system and the flame will decrease in volume. Accordingly the temperature of the parts will fall and the steam pressure subside, allowing the bellows 30 to contract or shorten with the result that the generator will be returned to its former position. 55 The promptness with which the fire responds to the different positions of the generator is enhanced by the changing water level in the generator due to the raising and lowering of the latter. For example, as the generator 60 rises and the relative water level therein

lowers the steam space increases and the steam pressure falls, immediately reducing the flame of the burner. The conditions are, of course, reversed on a lowering of the generator.

To regulate the average temperature of the fire, the screw 27 may be adjusted by turning the hand wheel 42 to change the relation between the beam 26 and the bellows 30. This will cause the generator 20 to be shifted with respect to the combustion chamber and consequently will alter the conditions which are responsible for the character of the flame.

Having thus described our invention, what we claim is:

1. In apparatus of the character set forth, the combination of an injector burner, a steam generator movable up and down toward and from a source of heat, water supply means having a substantially constant water level and communicating with the generator in such manner as to effect substantially the same water level in the latter, the generator tending to move by gravity in the latter of the aforesaid directions, flexible connections through which steam is conducted from the generator to the burner, means for supplying oil to the burner, and pressure operated means subjected to the steam pressure in the generator for moving the generator in the other of the aforesaid directions.

2. In apparatus of the character set forth, the combination of an injector burner, a steam generator movable up and down toward and from a source of heat and from which generator the burner receives its steam supply, water supply means having a substantially constant water level and communicating with the generator in such manner as to effect substantially the same water level in the latter means for supplying oil to the burner, pressure operated means subjected to the steam pressure in the generator, and adjustable connections between the last mentioned means and the generator, said pressure operated means serving to effect movement of the generator as aforesaid thereby to alter its elevation with respect to the aforesaid water level and vary the steam pressure delivered to the burner.

3. In apparatus of the character set forth, the combination of an injector burner, a pivotally supported element, a steam generator bodily carried by the element and sustained thereby in operative relation to a source of heat, water supply means having a substantially constant water level and communicating with the generator in such manner as to effect substantially the same water level in the latter, the generator being moved up and down toward and from said source by the rocking of said element upon its pivot, flexible connections through which steam is conducted from the generator to the burner,

means for supplying oil to the burner, pressure operated means subjected to the steam pressure in the generator, and connections between the last mentioned means and the 5 aforesaid element whereby the element is adapted to be swung on its pivot by said means.

4. In apparatus of the character set forth, the combination of a structure including a 10 combustion chamber, an injector burner arranged to discharge its products into said chamber, an element pivotally supported by the structure to swing on a horizontal axis adjacent the combustion chamber, a steam 15 generator bodily carried by said element above the combustion chamber so as to receive heat therefrom, water supply means having a substantially constant water level and communicating with the generator in such manner as to effect substantially the same water 20 level in the latter, pressure operated means subjected to the steam pressure in the generator, and operative connections between the last mentioned means and said element.

5. In apparatus of the character set forth, the combination of a structure including a 25 combustion chamber, an injector burner arranged to discharge its products into said chamber, an element pivotally supported by the structure to swing on a horizontal axis 30 below the combustion chamber, a steam generator bodily carried by said element above the combustion chamber to receive heat therefrom, water supply means having a substantially constant water level and communicating 35 with the generator in such manner as to effect substantially the same water level in the latter, pressure operated means subjected to the steam pressure in the generator, and 40 adjustable connections between the last mentioned means and said element.

6. In apparatus of the character set forth, the combination of an injector burner, a 45 steam generator exposed to a source of heat, a conduit leading from the steam generator to the burner, means for conducting fuel oil to the burner, means for varying the amount of heat delivered to the generator and for changing the water level in the generator 50 thereby to control the steam pressure delivered to the burner, and means operated by the steam pressure in the generator for actuating the last mentioned means.

7. In apparatus of the character set forth, 55 the combination of an injector burner, a steam generator exposed to a source of heat, a conduit leading from the steam generator to the burner, means for conducting fuel oil to the burner, a water receptacle, means for 60 maintaining a substantially constant water level within said receptacle, a conduit through which water gravitates from said receptacle to the generator, and means for raising and lowering the generator toward 65 and from the source of heat thereby to con-

trol the steam pressure delivered to the burner.

8. In apparatus of the character set forth, the combination of a vessel, means for supplying water thereto, means maintaining a 70 substantially constant water level in the vessel, a steam generator supported for movement toward and from a source of heat, connections through which the interior of the vessel above and below the water level thereof communicates with the top and bottom 75 portions of the generator, an injector burner, connections through which steam is conducted from the generator to the burner, means for supplying oil to the burner, and 80 pressure operated means subjected to the steam pressure in the generator for moving the generator away from the source of heat as the steam pressure increases, as and for the purpose specified.

9. In apparatus of the character set forth, the combination of an injector burner having a fixed position, a steam generator for supplying steam to the burner, flexible communicative connections between the generator and the burner, a source of water supply having a substantially constant level, a flexible conduit for delivering water from said source to the generator, the generator being 90 so related to said source as to have a water level in common therewith, means supporting the generator for substantially vertical movement toward and from the zone of intense heat of the burner flame, and means 95 for supplying oil to the burner.

10. In apparatus of the character set forth, the combination of an injector burner having a fixed position, a steam generator for supplying steam to the burner, flexible communicative connections between the generator and the burner, a source of water supply having a substantially constant level, a flexible conduit for delivering water from said source to the generator, the generator being 100 so related to said source as to have a water level in common therewith, means supporting the generator for substantially vertical movement toward and from the zone of intense heat of the burner flame, means for supplying oil to the burner, and pressure operated means subjected to the steam pressure in the generator for effecting movement of the generator as aforesaid thereby to vary 110 the steam pressure delivered to the burner.

In testimony whereof, we hereunto affix our signatures.
